CHARLES WILLIAM KENNON, OF TAMPA, FLORIDA, ASSIGNOR OF ONE-HALF TO
WILLIAM W. PEMBLE, OF LEESBURG, FLORIDA.

CINDER-GUARD.

1,393,627.

Specification of Letters Patent.

Patented Oct. 11, 1921.

Application filed July 1, 1921. Serial No. 481,881.

To all whom it may concern:

Be it known that I, CHARLES W. KENNON, a citizen of the United States, residing at Tampa, in the county of Hillsborough and 5 State of Florida, have invented certain new and useful Improvements in Cinder-Guards; and I do hereby declare that the following is a full, clear, and exact description of the invention, such as will enable others skilled 10 in the art to which it appertains to make and use the same.

The present invention relates to improvements in cinder guards for railway trains, and the primary object thereof is to provide 15 a cinder guard attachable to the car between adjacent windows thereof and including a body portion or space adapted to catch the cinders and placed in such a position that it will interpose an obstacle to the passage 20 of cinders into the following car window, and which further consists of a flue disposed in communication with the body portion of the guard and receiving the cinders therefrom, in which flue there is a draft induced 25 by the movement of the train to cause the cinders to be sucked downwardly to a point well beneath the window ledge and to there discharge the cinders.

Another object of the invention resides in 30 providing a cinder guard wherein the cinders will be caught and will be transmitted to a flue without their being apt to rebound over the sides of the guard and into the window, and wherein deflectors are provided in 35 order to check any such rebounding movement of the cinders and to cause such cinders to pass on to a flue through which they are exhausted to the atmosphere.

It is a further object of the invention to 40 provide an improved cinder guard of a simple and inexpensive construction and one which will constitute an ornament to railway cars and the like.

With the foregoing and other objects in 45 view, the invention will be more fully described hereinafter, and will be more particularly pointed out in the claims appended hereto.

In the drawings, wherein like symbols 50 refer to like or corresponding parts throughout the several views,

Figure 1 is a fragmentary side view of a railway car with a guard thereon, constructed according to the present invention;

55 Fig. 2 is a front elevation of the guard

with a portion of the screen removed and with parts shown in section;

Fig. 3 is a horizontal sectional view taken on the line 3—3 in Fig. 2; and

Fig. 4 is a fragmentary longitudinal sectional view taken on the line 4—4 in Fig. 3.

Referring more particularly to the drawings, 1 designates generally a railway car having adjacent windows 2 and 3, and 4 represents the panel between the windows. 60

In accordance with the present invention I have mounted my improved guard in the panel 4 between the windows 2 and 3. It is assumed in Fig. 1 that the railway car 65 is traveling to the left.

In accordance with the invention I provide the guard with a body portion and a flue which are intercommunicating, and which are both preferably formed of sheet metal in the same piece. The rear wall 5 75 of the body portion extends diagonally with respect to the line of draft so that cinders striking the said wall will be guided toward the outer portion of the guard and caused to enter the flue 6 which is disposed at this 80 point, and by which the cinders are exhausted to the atmosphere.

The flue 6 is made by coiling the sheet metal at the outer portion of the guard in a volute manner, thus forming a central 85 chamber 7 communicating with the body portion by volute passage 8. The extremity 9 of the sheet metal is folded over upon itself for the sake of strength and to constitute one wall of the internal chamber 7. The 90 sheet metal is offset outwardly upon itself at the forward portion of the flue to constitute an abutment 10 to which one end of the wire screen 11 may be attached. This abutment 10 also constitutes a stop for preventing cinders, which seek their way along the screen 11, from creeping over the flue and thus getting access to the windows.

The inner edge of the rear wall 5 of the guard is indicated at 12 and is secured as by 100 screws or other fastenings 13 to a strip 14 and to the window panel 4. The wire screen 11, which forms the front portion of the guard, can be made to extend at a right angle with respect to the car wall or at any other angle 105 desired. The space between the screen 11 and the rear wall 5 is preferably divided by a number of partitions 15 into a succession of compartments one above another. The partitions 15 are provided with later- 110

ally disposed flanges 16 on their inner faces through which rivets or other suitable fastenings pass to secure such flanges to the rear wall 5. The partitions 15 also constitute braces for the rear wall and for the screen 11.

V-shaped deflectors 18 are provided in conjunction with the partitions 15 and have their inner, angular portions soldered, 10 brazed, or otherwise secured to the outer portions of the partitions with their side wings extending diagonally and in divergent relation at opposite sides of the partition. These wings spread out in such fashion that they deflect the cinders toward the rear wall 5 at an angle other than a right angle which the cinders would ordinarily take were the deflectors left out. This is of 15 advantage as it directs the cinders on their rebound movement, if any, beneath the divergent wings of adjacent deflectors so that the cinders are pocketed in this manner and prevented from further escape from the 20 guard.

25 The flue is extended, as shown in Figs. 1 and 2, below the wall 5 and the other portions of the guard, and it has an open outlet at its bottom which lies well below the window sills for the discharge of the cinders 30 and other matter which may get into the guard. The discharge is at such a point that the cinders will not be apt to fly upwardly under the force of the air currents developed as the train moves. The air 35 passing beneath the lower discharge end of the flue will create a suction and a partial vacuum in the flue which will be relieved by the air through the screen 11 passing out of the volute channel 8 and down through 40 the chamber 7. The cinders are thus drawn in from all sides about the guard and effectively prevented from entering the window. A top 19 is provided for the guard which also 45 closes the upper end of the flue and prevents any induced draft at this point which would tend to lift the cinders and discharge them above the window.

It will be appreciated from the foregoing 50 that a cinder guard constructed and mounted as herein disclosed and operating in the manner described, will constitute an effective barrier against the entrance of cinders into railway car windows. It will also be obvious that the guard is of an inexpensive 55 construction inasmuch as the major portion

thereof is constructed of light sheet metal readily bendable into the shape necessary to form the guard and being desirably of a light construction so as not to add substantial weight to the car.

60 The screen 11 will avoid large cinders from entering the guard as these latter will fall by gravity downwardly over the face of the screen and fall by virtue of their weight beneath the windows. An apron 65 20 is provided by extending the wall 5 downwardly in order to effectively check any of these large cinders after getting below the screen 11. The outer ends of the deflector wings 18 are preferably curved, as indicated in Fig. 3, to lie close against the adjacent portion of the wall 6 of the flue in order to reinforce and strengthen the guard 70 generally.

75 It is obvious that various changes and modifications may be made in the details of construction and design of the above specifically described embodiment of this invention without departing from the spirit thereof, such changes and modifications being restricted only by the scope of the following 80 claims.

What is claimed is:—

1. An improved cinder guard comprising a body portion adapted to receive cinders, a 85 screen over the body part, and a flue communicating with the body part and adapted to convey the cinders therefrom below the line of a car window, substantially as described.

2. An improved cinder guard comprising a sheet metal body portion having a rear wall diagonally disposed with respect to the line of draft and adapted to guide the cinders toward the outer portion of the guard, 95 and a flue at such outer portion of the guard for receiving the cinders, said flue being composed of a volute channel having walls of sheet metal, and a screen over the front portion of the guard, substantially as 100 described.

3. A guard of the character described comprising a body portion, a number of partitions secured transversely in the body portion and dividing the same into a number of 105 compartments, V-shaped deflectors carried by the outer edges of said partitions, and a flue connecting with the various compartments, substantially as described.

CHARLES WILLIAM KENNON.
